(57) **CLAIM**

The ornamental design for a quick connect fluid connector component, therefor as shown and described.

DESCRIPTION

FIG. 1 is an isometric view of a fluid connector component, showing our new invention.

FIG. 2 is a front elevation view thereof.

FIG. 3 is a right side elevation view thereof with the left side elevation view being a mirror image thereof.

FIG. 4 is a rear elevation view thereof; and,

FIG. 5 is a top plan view of the fluid connector component according to the first embodiment with the bottom view being a mirror image thereof.

The broken lines in the figures are shown for the purpose of illustrating boundaries of the claimed design and the areas inside the broken line boundaries form no part of the claimed design.
